WATER TUBE BOILER CONSTRUCTION

Kingsley L. Martin, Montclair, N. J.

Application October 9, 1935, Serial No. 44,191

6 Claims. (Cl. 122—291)

The invention relates to steam boilers of the water tube type, and more especially to those having straight tubes inclined somewhat from the horizontal with water compartments at their ends and one or more steam and water drums above the tubes. It embodies improvements in the art of baffling this type of boiler over that disclosed in my U. S. Letters Patent No. 1,809,133, issued on June 9, 1931, and is the result of 10 experience with that construction.

The improvement consists in streamlining and arranging the baffles so as: (1) to decrease the resistance to the flow of gases through the boiler, thereby increasing the capacity of the boiler with 15 the chimney draft available; (2) to eliminate angles and corners which create eddy currents interfering with the gas flow; (3) to eliminate dead pockets where the gas does not circulate, and in which soot, cinders and fly ash accumulate; and (4) to increase the efficiency of the 20 boiler by insuring rapid flow of hot gases over practically the whole heating surface of the boiler with a minimum draft loss through the boiler.

These results are obtained without in any way 25 sacrificing those obtained by my previous construction, namely, partial cross flow of the gases over the tubes with the retention of hot refractory surfaces on the lower row of tubes in the most effective position to facilitate combustion 30 and to prevent smoke formation. One form of the invention is illustrated in the accompanying drawing, wherein:

Figure 1 is a longitudinal section partly in side 35 elevation of a steam boiler. Fig. 2 is a section on the line II—II of Fig. 1, showing the tile enclosing tubes in the lower row. Fig. 3 is a section on the line III—III of Fig. 1, showing tile laid on top of tubes to form a filter baffle.

Referring now to the drawing, 1 is the front 40 wall of a furnace, 2 is the bridge wall, and 3 the upper part of the combustion chamber. The water tubes 4 are located above the furnace and may be in one group, as shown, or subdivided into two or more groups, but the grouping is not material to my invention. The tubes are connected at the rear end to downtake headers 5 and at the front end by uptake headers 6. The uptake headers are connected to the longitudinal drum by short connections 8 and the downtake headers by a long connection 9. In certain forms of boilers a cross drum is used, but this is not material to my invention.

The baffle construction consists of five parts as follows:

First, a short longitudinal baffle 10, which is

constructed of tile that preferably, but not necessarily, completely surrounds the tubes in the lower row for only a part of their length, so as to present a continuous refractory surface to the hot gases leaving the furnace.

Second, a curved rear cross baffle 11 inclined toward the rear header 5. The inclination and curvature tend to prevent the accumulation of soot and slag, decreases the entering velocity of the gases into the first pass 19, maintains substantially uniform velocity of the gases as they decrease in volume due to cooling action of the tubes over which they pass, and forces the gases to flow across the tubes so they impinge on the tubes and maintain the maximum rate of heat transfer.

Third, a curved upper cross baffle 12 inclined toward the front header 6 is used to reverse the direction of the gases and direct them downward across the tubes, forming with the rear cross baffle a second pass 21. After a second reversal in the lower part of the tube space below the baffle 12, the gases again cross the tubes in the third pass 20 and flow to the outlet 14 of the boiler.

Fourth, a straight upper baffle 13 is laid, preferably on the upper row of tubes, in order to prevent the gases which are ascending the first pass 19 from flowing directly to the boiler outlet 14. This baffle in conjunction with the baffle 12 directs the gases downward into the second pass 21.

Fifth, a curved front cross baffle 15 connecting with the lower longitudinal baffle 10 and inclined upward across the tubes to a point on or adjacent to the front header 6, forms with the upper cross baffle 12, the third pass 20 and with the front header 6, a fourth pass 16.

The advantages of this construction will be evident to those skilled in the art. The curved cross baffle 15 converts what would be, with the usual form of construction, a dead gas pocket, in which soot and ashes would accumulate, into an active and useful part of the boiler. Not only are the front ends of the lower rows of tubes exposed to the radiant heat of the fire, but by leaving a narrow opening 17 between the front cross baffle 15 and the front header 6, a small portion of the hot furnace gases are diverted from the main stream and caused to flow across the heating surface in the fourth pass 16, materially increasing the effective heating surface of the boiler. A similar narrow opening 18 between the upper longitudinal baffle 13 and the rear header 5 diverts a small portion of the gas

ascending through the first pass 19 into and through the space between the tubes at the upper rear end of the boiler where an effective flow of gases would not otherwise exist. The longitudinal baffle 10 reflects the heat into the gas stream passing below it, and by maintaining a high gas temperature, aids materially in securing complete combustion and in the prevention of smoke.

10 The curved baffle construction in conjunction with the proper proportioning of the various passes will maintain a uniformly high velocity of the gases and retain the soot and ash in suspension until clear of the third pass 20. Suitably located soot blowers at the base of the curved lower baffles will readily keep the tube and baffle surfaces clean.

15 In order to more evenly distribute the hot gases flowing into and through the first pass 19 and through and out of the third pass 20, filter baffles 22 and 23 may be used in one or both passes and may readily be constructed of loose tile laid on top of the tubes in some, but not all, of the alleys or spaces between the tubes. The filter 20 baffles need not be gas tight and may be of such length as may be found necessary to accomplish the desired result. An alternate construction which would produce the same results would be a checker work formed by using tile 25 spaced at intervals in the alleys. It is also evident that the filter baffles may be located in the passes instead of at the throats, as shown, or may be used alone, or in conjunction with each other, and either or both may be used with 30 either straight or curved cross baffles.

35 While certain embodiments of the invention are shown in the accompanying drawing, it should be understood that there is a wide variation possible in the types of boilers, in the grouping of their tubes, and in the location of superheaters (if used), and I do not limit the application 40 of my invention to the exact construction shown unless otherwise limited by the terms of the claims. While curved cross baffles are more 45 effective than straight baffles, it is evident that straight cross baffles may be used instead, and I do not limit my claims to one construction only.

What I claim is:

50 1. In a boiler of the water tube type having a furnace therebeneath and comprising a bank of tubes inclined from front to rear, upright headers at the ends of the tubes and a steam and water drum above the tubes with which the tubes communicate through the headers, a combustion chamber below the tubes, a longitudinal baffle extending along the tubes in the lower row intermediate the ends thereof for a portion only of their length, a cross baffle extending upwardly 55 from the rear end of said longitudinal baffle diagonally across the tubes towards the rear header, a second cross baffle extending upwardly from the front end of said longitudinal baffle diagonally across the tubes toward the front header, a second longitudinal baffle on one of the upper rows of tubes extending forwardly a part only of the length of the tubes and a third cross baffle extending downwardly from the front end of said upper longitudinal baffle diagonally across the tubes toward the front header.

55 2. In a boiler of the water tube type, having a furnace therebeneath and comprising a bank of tubes inclined from front to rear, upright headers at the ends of the tubes, and a steam and water drum above the tubes with which the tubes com-

municate through the headers, a combustion chamber below the tubes, a longitudinal baffle extending along the tubes of the lower row intermediate the ends thereof for a portion only of their length, a cross baffle extending upwardly 5 in a curve across the tubes towards the rear header, a second cross baffle extending upwardly in a curve from the front end of said lower longitudinal baffle across the tubes toward the front header, a second longitudinal baffle on top of 10 one of the upper rows of tubes extending forwardly a part only of the length of the tubes and a third cross baffle extending in a curve downwardly across the tubes toward the front header.

15 3. In a boiler of the water tube type, having a furnace therebeneath and comprising a bank of tubes inclined from front to rear, upright headers at the ends of the tubes and a steam and water drum above the tubes with which the tubes communicate through the headers, a combustion chamber below the tubes, a longitudinal baffle extending along the tubes of the lower row intermediate their ends for a portion only of their length, a cross baffle extending upwardly from 20 the rear end of said longitudinal baffle diagonally across the tubes towards the rear header, a second cross baffle extending upwardly from the front end of said longitudinal baffle diagonally across the tubes toward the front header, a second longitudinal baffle on one of the upper rows of tubes, extending forwardly a part only of the length of the tubes, and a third cross baffle extending downwardly from the front end of said upper longitudinal baffle diagonally across the tubes towards 25 the front header, a filter baffle extending forwardly from the forward end of said second longitudinal baffle towards the front header, and a filter baffle extending to the rear from the rear 30 end of the first mentioned longitudinal baffle towards the rear header.

4. In a boiler of the water tube type having a furnace therebeneath and comprising a bank of tubes inclined from front to rear, upright headers at the ends of the tubes and a steam and water drum above the tubes with which the tubes communicate through the headers, a combustion chamber below the tubes, a longitudinal baffle extending along the tubes in the lower row intermediate the ends thereof for a portion only of their length, a cross baffle extending upwardly 45 from the rear end of said longitudinal baffle diagonally across the tubes to a point adjacent the front header but spaced away therefrom, a second longitudinal baffle on one of the upper rows of tubes extending forwardly a part only of the length of the tubes and a third cross baffle extending downwardly from the front end of said upper longitudinal baffle diagonally across the 50 tubes toward the front header.

5. In a boiler of the water tube type having a furnace therebeneath and comprising a bank of tubes inclined from front to rear, upright headers at the ends of the tubes and a steam and water 55 drum above the tubes with which the tubes communicate through the headers, a combustion chamber below the tubes, a longitudinal baffle extending along the tubes in the lower row intermediate the ends thereof for a portion only of their length, a cross baffle extending upwardly from the rear end of said longitudinal baffle diagonally across the tubes toward the front header, a second longitudinal baffle on one of the upper 60 rows of tubes extending forwardly over a

substantial portion of the length of such tubes from a point adjacent to the rear header but spaced away therefrom, and a third cross baffle extending downwardly from the front end of said upper longitudinal baffle diagonally across the tubes toward the front header.

- 5 6. In a boiler of the water tube type having a furnace therebeneath and comprising a bank of tubes inclined from front to rear, upright headers at the ends of the tubes and a steam and water drum above the tubes with which the tubes communicate through the headers, a combustion chamber below the tubes, a longitudinal baffle extending along the tubes in the lower row intermediate the ends thereof for a portion only of their length, a cross baffle extending upwardly
- 10
- 15

from the rear end of said longitudinal baffle diagonally across the tubes towards the rear header, a second cross baffle extending upwardly from the front end of said longitudinal baffle diagonally across the tubes to a point adjacent 5 to the front header but spaced away therefrom, a second longitudinal baffle on one of the upper rows of tubes extending forwardly over a substantial portion of the length of such tubes from a point adjacent to the rear header but spaced 10 away therefrom, and a third cross baffle extending downwardly from the front end of said upper longitudinal baffle diagonally across the tubes toward the front header.

KINGSLEY L. MARTIN.
